UNITED STATES PATENT OFFICE.

ARTHUR C. ROWLEY, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA.

SPRINKLER-HEAD.

1,267,907.

Specification of Letters Patent. Patented May 28, 1918.

Application filed September 28, 1917. Serial No. 193,712.

To all whom it may concern:

Be it known that I, ARTHUR C. ROWLEY, a citizen of the United States, residing in Philadelphia, Pennsylvania, have invented 5 a Sprinkler-Head, of which the following is a specification.

One object of my invention is to provide a sprinkler head which shall include a novel arrangement of valve and fusible link particularly designed to facilitate the assembling of the parts and their subsequent retention in certain definite positions;—another object being the provision of a novel form of fusible link having its parts so designed and arranged that there is but a relatively small leverage on the soldered joint. As a consequence higher pressures may be applied to said link with a view to increasing its certainty of action under predetermined conditions. 15

I further desire to provide a novel form of fusible link which in addition to possessing relatively extensive coöperating soldered surfaces, shall likewise have a relatively high structural strength in order that it may remain in condition to satisfactorily perform its functions regardless of the effects of corrosion.

I also desire to provide a link whose parts 20 may be conveniently made of stamped or pressed metal and which shall be of such form as to be conveniently assembled;—the invention also contemplating a simple and substantial form of sprinkler head including 25 a fusible link mounted to serve as a compression-resisting strut of such design as to insure the separation of its parts and the operation of the sprinkler when the temperature in its vicinity rises to or above a predetermined point.

These objects and other advantageous ends I secure as hereinafter set forth, reference being had to the accompanying drawings, in which—

45 Figures 1 and 2 are respectively front and side elevations of a sprinkler head constructed according to my invention;

Fig. 3 is a vertical section of the solder-connected elements forming part of the link devised by me;

Figs. 4 and 5 are perspective views of the valve and its washer forming part of the sprinkler head; and

Figs. 6, 7, 8 and 9 are perspective views of the parts of the fusible link. 55

In the above drawings, 1 represents the tubular body of the sprinkler head which has one end externally threaded for attachment to the pipes of a sprinkler system. The opposite end of this body is formed to provide a valve seat 3 on which is mounted a dished washer 4 and a valve 5. The latter is characterized by having on its outer face a projecting boss 6 transversely slotted at 7 and having at the center of this slot a projection 8 designed to enter a correspondingly formed recess 10 in one end of a fulcrum plate 9 hereafter referred to. 60

Projecting upwardly from opposite sides of the body 1 are the arms 11 of a yoke 70 which at its central portion is thickened to provide a boss 12 which has an internally threaded passage for the reception of a screw 13 forming an abutment axially in line with the center line of the valve 5 and 75 also with the passage through the body 1. Mounted on this screw is a water deflecting plate 14.

For maintaining the valve on its seat against the pressure of the air in the sprinkler system, I provide a strut in the form of a fusible link which in its preferred form consists of the fulcrum plate 9, one of whose ends is centered upon the boss 6 of the valve 5 as above noted and whose opposite end is 85 engaged by one arm of a flying lever 15. This latter consists of a length of metal strip bent or otherwise formed so that its two parts extend at an angle to each other of slightly more than 90° and its short arm 90 adjacent its free end is provided with a depression for the reception of the pointed end of the screw 13;—it being noted that the fulcrum plate 9 engages this short arm between said depression and the main part of the 95 long arm.

The free end of said long arm extends through a slot 16 in one part of a keeper plate 17 whose second part extends substantially at right angles to said first part, parallel with and immediately adjacent to one face of the fulcrum plate 9. A latch 18 has a flat body portion parallel with and immediately adjacent the other face of the fulcrum plate, and includes a tongue 19 projecting through a slot 20 in the fulcrum plate 100

and also through a second slot 21 in the keeper plate; its extremity being bent down parallel with its body and lying parallel with and immediately adjacent the external 5 face of the keeper plate 17,—constituting a hook in effect.

For properly positioning the elements 18, 9 and 17, the first of these is provided with a central circular depression 22 and the fulcrum plate is pressed out on one side to form a projection designed to enter said depression 22 and on its opposite face to form a depression 23 for the reception of a circular projection 24 on the keeper plate. The free 10 end of the long arm of the flying lever 15, like the end of the tongue 19 of the latch, has the form of a hook indicated at 25, for preventing its accidental withdrawal from the slot 16 of the keeper plate 17. The short 15 arm of this lever has a transverse depression 26 formed in its face for the reception of the upper end of the fulcrum plate and also has a central longitudinally extending rib 27, for stiffening and strengthening it.

25 Under conditions of use the tongue 19 of the latch is inserted through the slots 20 and 21 of the fulcrum and keeper plates when these occupy the relative positions shown in Fig. 3 and thereafter these three 30 elements are soldered or sweated together by an alloy or metal having a definite low fusing point.

The lower end of the fulcrum plate is then centered on the top of the valve 5 after this 35 with its washer 4 has been mounted on the valve seat, and the long end of the fulcrum lever is hooked into the slot 16, after which the upper end of the fulcrum plate is caused to enter its transverse notch or recess 26. 40 The screw 13 in the yoke is then entered in the depression 28 of the short arm of said lever and is set up until it exerts a predetermined and relatively high pressure upon said arm. Obviously this pressure tends to 45 cause the hooked end of the long arm to draw the projecting part of the keeper plate away from the fulcrum plate, but this action is prevented by the hooked or projecting arm of the latch 18 whose body is soldered 50 to the distant side of said fulcrum plate; the valve being held in place against the pressure in the sprinkler system by reason of the pressure exerted on this latter plate.

When the fusible metal connecting the 55 elements of the link is melted or sufficiently softened by a predetermined rise of temperature, the pressure of the screw on the flying lever causes the latter to turn on the fulcrum plate and to draw the keeper plate 60 away from the same, thereby swinging the latch on its tongue as a pivot as its body likewise moves away from said fulcrum plate, until said latch assumes such a position as to free said keeper plate. The latter then permits the flying lever to turn on

the fulcrum plate to an extent sufficient to permit the latter to fall or to be forcibly moved to one side by the pressure exerted on the valve, which thereupon is forced off of its seat and permits the escape of air and 70 water from the passage in the body 1.

It is particularly to be noted that the bodies of the latch and the fulcrum and keeper plates are preferably made in the form of broad flat sheets or plates having 75 relatively large solder-connected areas, with the result that the link as a whole will possess comparatively great structural strength and thus permit of the screw 13 being set up to exert a comparatively high pressure on 80 the lever 15.

Moreover, owing to the fact that the outward pull or tension exerted on the horizontal arm of the keeper plate is transmitted directly to the tongue 19 of the latch, the 85 leverage on the soldered joint between the body of said latch and the fulcrum plate may be reduced to a small amount, so that there is but a relatively low stress on the fusible metal of said joint. Altogether the 90 fusible link is substantial, reliable and not likely to fail either by reason of the corrosion of the fusible metal on the one hand, or by such a sticking of its parts as to prevent their separation when exposed to a pre- 95 determined temperature.

It is further to be noted that the parts of the link are of such forms as to be conveniently made of stamped or pressed up sheet metal, thereby permitting of their accurate 100 and relatively inexpensive manufacture.

It is particularly to be noted that while I have described the fusible link forming part of my invention as having certain of its elements engaged by a valve and an abutment 105 respectively, said link may be used in other combinations and other members substituted for the two noted, without departing from my invention.

I claim;—

1. The combination in a sprinkler head of a valve; an abutment; and a fusible link including a lever engaging one of said parts, a fulcrum plate engaging the other part and the lever, with means including a latch, a keeper plate, and relatively fusible material separably connecting said latch and keeper plate to the fulcrum plate, for normally holding said lever in place.

2. The combination in a fusible link of a lever having two portions substantially at right angles to each other; a fulcrum member engaging one of said portions; and two plates having relatively fusible material separably connecting them to the fulcrum member, one of said plates having a tongue connecting the fulcrum member with the other plate, and said second plate having a portion engaging the second portion of said lever.

3. The combination in a fusible link of

three substantially parallel plates; relatively fusible material separably connecting said plates, one plate having a tongue connecting the other plates, the second plate having a 5 projecting arm; with a lever engaging the third plate and also the projecting arm of the second plate.

4. The combination in a fusible link of three plates of which two have openings and 10 the third includes a tongue extending through said openings; relatively fusible material separably connecting said plates;

with a lever fulcrumed on one of the plates and engaged by another of the plates.

5. The combination of a fulcrum plate; a 15 keeper plate adjacent and substantially parallel therewith; a hook member extending through and lying substantially parallel with said two plates for separably connecting the same; fusible material connecting the plates 20 and the member; and a lever hooked to one of the plates and fulcrumed on the other.

In witness whereof I affix my signature.

ARTHUR C. ROWLEY.
